CLAIM

The ornamental design for a digital signage with display stand as shown and described.

DESCRIPTION

FIG. 1 is a top, front and right-side perspective view of a digital signage with display stand showing our new design; FIG. 2 is a bottom, front and left-side perspective view thereof;

FIG. 3 is a front elevation view thereof, a rear elevation view being a mirror image thereof;

FIG. 4 is a left-side elevation view thereof, a right-side elevation view being a mirror image thereof;

FIG. 5 is a top plan view thereof;

FIG. 6 is a bottom plan view thereof; and,

FIG. 7 is a perspective view thereof, shown in a state of use. The broken lines showing product image and information in FIG. 7 are for the purpose of illustrating an environment of use and form no part of the claimed design.

1 Claim, 7 Drawing Sheets(56)
